Attorney

UNITED STATES PATENT OFFICE

CHARLES W. EBELING, OF NEW YORK, N. Y., ASSIGNOR TO PHONODISC CORPORATION,
OF NEW YORK, N. Y., A CORPORATION OF NEW YORK

FRICTION CLUTCH FOR SOUND REPRODUCING MACHINES

Original application filed September 23, 1929, Serial No. 394,571. Divided and this application filed
October 21, 1930. Serial No. 490,209.

This invention relates to improvements in sound reproducing machines, the same being a division of the application filed September 23, 1929, Serial #394,571, and relating more particularly to the mechanism by means of which the turn table is connected to the driving mechanism in a sound filtering relation.

Another object of this invention is the provision of a sound deadening brake device interposed between the turntable and the spindle, whereby when the spindle is started or stopped, the inertia of the turntable is taken care of, and thus the instant starting or stopping of the turntable is accomplished, the brake device also acting as a sound deadening or filtering means in conjunction with the driving gear as set forth in the parent application.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings:

Figure 1 is a side elevation of a complete sound reproducing machine with the present invention applied thereto.

Figure 2 is a perspective view of the sound deadening and braking device forming the coupling between the turntable and the operating spindle.

Referring to drawings the present device includes a main casing or base 5, which in turn supports a base plate 6. This base plate 6 has mounted thereon, a casing 7 in which is mounted the driving mechanism (not shown) for the spindle 22 to which spindle is attached a casting 8 rotatably mounted within the socketed member 9 of the casing 7. The member 8 is provided with an arm

23, which in turn carries a pin 24 by means of which the turntable brake and transmission attaching member is attached. This latter member as clearly shown in Figure 2 consists of a resilient plate or strip 25 of bent metal, the same being provided with apertures 31 and 32 which loosely surround the pin 24 so that the apertured terminal 38 which surrounds the shaft 22, and is out of contact therewith, will carry the braking annulus 29 upon the upper face thereof, the purpose of which will presently appear. The short terminal 30 of the member 25 as illustrated, rests upon the upper surface of the arm 23 and assists the device in exerting an upward resilient tension so that as the turntable 26 is placed upon the spindle 22, as illustrated in Figure 1, the concentric annular brake portion 35 upon the under side of the turntable will rest and bear upon the braking annulus 29 and cause a slight flexing of the member 25, the said member being sufficiently stiff to slightly and resiliently resist the weight of the turntable and produce a braking action between the portion 35 of the turntable and the braking annulus 29 and thus providing a sound filtering transmission clutch between the spindle 22 and the turntable 26.

What is claimed is:

1. A sound reproducing machine including a driven spindle, a turn table detachably mounted thereon, and a resilient connecting medium between the two carried by the spindle and exerting a clutch action against the turntable, said resilient connecting medium including a detachable device having two spaced terminals one of which is adapted to be connected to the spindle and the other of which is provided with a frictional engaging member for contacting the turntable.

2. A sound reproducing machine including a driven spindle, a turntable detachably mounted thereon, and a resilient connecting medium between the two carried by the spin-

idle and exerting a clutch action against the turntable, said resilient connecting member consisting of an arm carried by the spindle and provided with an upstanding pin, a metal plate bent to provide a substantially V shaped apertured portion for engaging the pin with one terminal raised upon the arm, said plate being provided with an extension from the remaining terminal formed to surround the spindle but not to contact same, and a co-acting braking means carried by the latter and the adjacent portion of the turntable and forming a frictional clutch connection between the two.

15 In testimony whereof I affix my signature.
CHARLES W. EBELING.
